(57) **CLAIM**

I claim the ornamental design for an insert bit, as shown and described.

DESCRIPTION

FIG. 1 is a front perspective view of a first construction of an insert bit of the present invention.

FIG. 2 is a right side view of the insert bit of FIG. 1, with the left side view being identical to the right side view.

FIG. 3 is a top view of the insert bit of FIG. 1, with the bottom view being identical to the top view.

FIG. 4 is a front view of the insert bit of FIG. 1; and,

FIG. 5 is a rear view of the insert bit of FIG. 1.

The portions of the insert bit shown in broken lines are included for the purpose of illustrating environment and form no part of the claimed design. The portions of the insert bit shown in broken lines having unequal length segments illustrate the boundary of the claimed design and form no part of the claimed design.
